Des. 103

Thomas Barry, (assignor of S. N. Ranson) of New York, N.Y.
Letters Patent (Design No. 103) dated 5th January 1847.

The schedule referred to in these Letters Patent and making
part of the same

To all whom it may concern: Be it known that I, Thomas Barry of New York in the County and State of New York, have invented a new design for an ornamental air tight stove, and I do hereby declare that the accompanying drawings making part of this Specification, are full and exact representations thereof. Fig. 1, being a perspective view of a stove after my design, and figs. 2, 3, 4 & 5, representations of portions of detached plates upon a larger scale to shew the detail of ornament. The whole is after the style of Louis XIV.

Fig. 2 is a portion of a side; Fig. 3. an end; Fig. 4. a part of the top; and Fig. 5 a portion of the hearth or bottom plate, the ornaments consisting of repetitions of the figures shown in the drawings, which figures cannot be easily described in words, but are fully represented. The sides and ends are respectively similar to each other. The whole is crowned by a base & Fig. 1.
